UNITED STATES PATENT OFFICE.

GEORGE PIRRUNG AND FELIX PIRRUNG, OF RAVENSWOOD, ILLINOIS.

BED-LOUNGE.

SPECIFICATION forming part of Letters Patent No. 477,449, dated June 21, 1892.

Application filed January 21, 1892. Serial No. 418,788. (No model.)

To all whom it may concern:

Be it known that we, GEORGE PIRRUNG and FELIX PIRRUNG, citizens of the United States, residing at Ravenswood, in the county of Cook and State of Illinois, have invented certain new and useful Improvements in Bed-Lounges, of which the following is a specification.

This invention relates to improvements in bed-lounges, and is especially adapted to that class of such lounges which may be folded together and used as a settee or sofa during the day and then unfolded and employed as a bed at night; and it consists in certain peculiarities of the construction and novel arrangement of the various parts thereof, as will be hereinafter more fully set forth and specifically claimed.

The ordinary bed-lounge or sofa, in order that its proportions may be harmonious and that it may present a more attractive piece of furniture when folded, is somewhat too short to comfortably accommodate a full-grown person as a bed; and it is the object of our invention to so construct a lounge that when opened additional length may be gained by the employment of our construction, which is simple and inexpensive, and can be readily closed and concealed within the folding parts of the bed.

In order to enable others skilled in the art to which our invention pertains to make and use the same, we will now proceed to describe it, referring to the accompanying drawings, in which—

Figure 1 is a view in side elevation, partly in section, showing the device open or in position to be used for a bed. Fig. 2 is a plan sectional view thereof. Fig. 3 is a detailed perspective view of one of the foot-extension pieces detached. Fig. 4 is a similar view of one of the pillow-rests, and Fig. 5 is a like view of a modification thereof.

Similar letters refer to corresponding parts throughout the different views of the drawings.

A represents the main frame or bed of our lounge, which is supported at its rear by the ordinary stationary legs (not shown) and in front by legs a, which are pivotally secured in the ordinary manner to the movable portion or frame B, the upper portion of which,

when folded, is provided with a cushion or upholstery C' for a seat.

As seen in Figs. 1 and 2, the main frame of the lounge is composed of a back piece A', which is in an upright position and has rigidly fixed to it, near its bottom, a floor or frame A², which is provided with a number of springs b, usually spiral in form, for the support of the mattress and other bedding. At each end this floor is provided with end pieces c and c', which encompass the springs b and the bedding. To the outer edge of the floor or frame A² is hinged in any desired manner the frame or flooring B, which is likewise provided at each end on its upper surface when unfolded with pieces c and c' for a similar purpose as those on the frame A². To the inner surfaces of the end pieces c' of the frames A² and B and near the edges of said frames are secured by means of staples d or otherwise, if desired, the foot extension-pieces C. These pieces are preferably made of one piece of wire formed, as shown in Fig. 3, at their ends with a loop or eye e to engage with the staple or hook d. The wire composing the piece C is formed so as to extend in an upright position till flush with the upper surface of the end piece c' and is then bent outward at substantially a right angle for a distance about equal to the height of the end piece c', and is then again bent upward and at substantially a right angle and then laterally at a right angle, so that the free end of the piece will extend transversely to the frames. It will therefore be seen and understood that as the ends or eyes of the pieces C are secured near the edges and floors of each of the frames they (the pieces C) will straddle the mattresses and can be readily folded over to the position indicated by dotted lines in Fig. 1, when their transverse portions e' will rest on the bedding and assist in securing the same in place when it is desired to fold the frames together.

In order to more securely hold the pieces C in an upright and extended position, as shown in Fig. 1, we secure a spring H to each of the end pieces c' by means of a staple h or otherwise and allow its free end to press the upright part of the piece C against the end piece c', as is clearly seen and will be readily understood by reference to Fig. 2. When it is de-

sired to fold the pieces over to the position indicated by dotted lines in Fig. 1, the spring H will be pressed downward by the upright portion of the piece C, as is evident, yet will 5 be in position to hold it in the upright position as soon as it is folded.

At the opposite ends or the head of the frames A² and B, and preferably to the upper surface of the floors thereof and near their

- 10 edges, are secured in any desired manner the pillow-rests, each of which is made of two pieces of wire, as is clearly seen in Figs. 4 and 5 of the drawings. The lower portion D' of these rests has its ends secured to the floors
- 15 of the frames, as above stated, and is so formed as to extend longitudinally therewith toward the middle of the frames, when it is bent back upon itself till near the end pieces c, when the two sides d' are united by
- 20 the transverse bend d², at each corner of which is provided a loop d³, with which the ends of the upper portion D², which are formed with eyes d⁴, engage. The upper portion D² is formed, as shown, into three sides of a rect- 25 angle and engages at its ends by means of the eyes d⁴, which encircle the front parts of the loops d³, the rear portions of which serve as a support and keep the piece D² in an inclined upright position over the end piece c, thus extending the length of the bed in this 30 direction.

By reference to Figs. 1 and 2 it will be seen that the portions D' of the pillow-rest D extend some distance from the end pieces c and 35 will thereby form a spring-support for that portion of the bedding upon which the heavier portion of the body rests, and will also dispense with the use of so many spiral springs at this point, and, furthermore, that the upper or hinged portion D² will stride the bedding and may be folded to the position indicated by dotted lines when it is desired to 40 close the lounge.

In Fig. 5 we have shown a modification of the pillow-rest which we may sometimes use, 45 in which the construction is identical with that above described, except that its lower portion D³ is formed with coils d⁵ at its inner ends, and in Fig. 2 we have shown this modified form attached to the frame A², while the 50 frame B is supplied with the other construction.

While we prefer to use both the pillow-rests and foot-pieces, yet it is evident that we may omit either without departing from our invention. 55

Having thus fully described our invention, what we claim as new, and desire to secure by Letters Patent, is—

1. In a bed-lounge, the combination of the 6c main frame A, having the flooring or frame A², having the end pieces c c' and rigidly secured thereto, with the frame B, having the end pieces c c' and hinged to the frame A², the foot-pieces C, having the springs H and secured at one end of the frames, and the pillow-rests secured at the other ends of the frames, all constructed, arranged, and operating substantially as and for the purpose set forth. 7c

2. In a bed-lounge, the combination of the frame A², having the end pieces c c', with the frame B, having the pieces c c', the foot-pieces C, made of one piece of wire and secured at one end of the frames, the pillow-rests D, having the lower or spring portion D', having the loops d³, and the upper portion d², having the eyes d⁴ to engage the loops and secured at the other ends of the frames, substantially as and for the purpose set forth. 75

GEORGE PIRRUNG.
FELIX PIRRUNG.
